Daniel Wilson ^{Design.}

N° 871. Parlor Cooking Stove

Patented Feb. 10. 1857.

Des. 871

Dan'l Wilson, of Nashua, N. H.

Assignor to

Union Stove Company, of Nashua, N. H.

Letters Patent No. 871. Dated Feb. 10th 1857

The Schedule referred to in these Letters Patent and making part of the same.

To all whom it may concern:

Be it known, that I, Daniel Wilson, of Nashua, in the County of Hillsborough, and State of New Hampshire, have invented or produced a new and original design for a Parlor Cooking Stove, and I do hereby declare that the following is a full, clear, and exact description of the same.

The accompanying drawing shows a front elevation of the stove with the various ornaments and mouldings formed thereon which constitute my invention. A proper pattern should be formed for each of the parts constituting the front as a whole, and the stove top and top ornament thereto.

The front plate immediately before the fire or grate is made so as to be conveniently removed, when desired, the carving of these several pieces being in relief as indicated in the annexed cut or drawing.

The back of the stove, and its ends can be formed in any desired shape or form to allow of a spacious oven and fire place for the grate and coal therein.

Having thus described the nature of my design by the accompanying drawings.

I claim the design, configuration and arrangement in bas relief, on the front and top of the stove
